UNITED STATES PATENT OFFICE.

PETER M. WEBER, OF HOMESTEAD, PENNSYLVANIA.

UNIVERSAL ROLLING-MILL.

SPECIFICATION forming part of Letters Patent No. 684,658, dated October 15, 1901.

Application filed November 21, 1900. Serial No. 37,255. (No model.)

To all whom it may concern:

Be it known that I, PETER M. WEBER, a citizen of the United States of America, residing at Homestead, in the county of Allegheny and State of Pennsylvania, have invented certain new and useful Improvements in Universal Rolling-Mills, of which the following is a specification, reference being had therein to the accompanying drawings.

10 This invention relates to certain new and useful improvements in rolling-mills, and is an improvement upon my Patent No. 645,409, bearing date of March 13, 1900.

The present invention has for its object to 15 construct a universal mill wherein the horizontal and vertical rolls are adjustable and provide means whereby the horizontal will impart or communicate a rotary movement to the vertical rolls; furthermore, provide means 20 whereby the horizontal rolls will be connected at all times to the vertical rolls irrespective to any adjustment of said rolls.

In my former patent I have shown a pair 25 of horizontal and vertical rolls; but the vertical rolls were driven by the frictional engagement of the blank to be rolled, and I find that a great advantage is obtained by connecting means to the horizontal rolls that will 30 impart a constant rotary movement to the vertical rolls.

Another object of my present invention is 35 to provide means whereby a perfectly smooth beam or the like may be rolled with less friction than heretofore and preventing any liability of the vertical rolls stopping in case a great pressure is bearing against them when the same are driven by frictional engagement.

I have found by the use of my improvements 40 there will be less wear and tear of the working parts of the machine. Consequently the lifetime of the same will be prolonged in this manner.

With the above and other objects in view 45 the invention consists in the novel combination and arrangement of parts to be hereinafter more fully described, and specifically pointed out in the claims.

In describing the invention in detail reference is had to the accompanying drawings, 50 forming a part of this specification, and where-

in like numerals of reference indicate corresponding parts throughout the several views, in which—

Figure 1 is a side elevation of my improved universal mill. Fig. 2 is a front view thereof. Fig. 3 is a side elevation of the vertical and horizontal rolls, the latter being partially broken away. Fig 4 is an underneath plan view of the vertical roll.

In the drawings, the reference-numeral 1 represents the housings, 2 the upper horizontal roll, and 3 the lower horizontal roll, the latter roll being provided with cog-wheels 4 on each side thereof, said cog-wheels being adapted to mesh with the cogs 5 of the vertical 65 rolls 6, said cogs 5 being arranged on the under face of said rolls 6 and extending radially around the periphery of said rolls, said horizontal and vertical rolls being adjustable for the purpose of rolling different thicknesses 70 of beams.

The operation of my improved rolling-mill is as follows: The horizontal rolls 2 and 3 being driven in the usual and well-known manner, the lower roll 3, carrying with it the cog-wheels 4, will communicate a direct rotary movement to the vertical roll 6, the latter being driven in unison with the rolls 2 and 3 as the blank is formed between the horizontal and vertical rolls.

The many advantages obtained by the use of my improvements will be readily apparent from the foregoing description and by referring to the accompanying drawings.

Particular attention is directed to the fact 85 that the arrangement as herein described may be attached to the upper roll instead of the lower one and may be operated in the same manner; furthermore, that other means may be employed carried by one or both of the 90 horizontal rolls to communicate a direct rotary movement to the vertical rolls and that other changes may be made in the details of construction without departing from the general spirit of my invention, and the vertical 95 rolls are adjusted inwardly and outwardly, as shown in the drawings.

In the drawings of my prior patent, as well as the present invention, I have shown the vertical rolls constructed in a plain cylin- 100

drical form; but I do not wish to limit myself to this construction, as the same may be mounted upon bearings or shafts when desired. It will also be noted that the horizontal rolls may be adjusted upwardly and downwardly, either one roll or the other roll, as may be found most expedient.

Having thus fully described my invention, what I claim as new, and desire to secure by Letters Patent, is—

1. In a universal rolling-mill, the combination of horizontal adjustable rolls, vertical adjustable rolls, cog-wheels arranged to one of said horizontal adjustable rolls, cogs arranged upon one end of each of the said vertical adjustable rolls to communicate a rotary

movement to the said vertical rolls irrespective of the adjustment of the latter.

2. In a universal rolling-mill, the combination of horizontal adjustable rolls, cog-wheels arranged to the lower horizontal adjustable roll, vertical adjustable rolls, cogs arranged on the lower end of each of the vertical adjustable rolls to communicate a rotary movement to the said vertical rolls irrespective of the adjustment of the latter.

In testimony whereof I affix my signature in the presence of two witnesses.

PETER M. WEBER.
